UNITED STATES PATENT OFFICE.

RAY MOSHER SMITH, OF NEW YORK, N. Y., ASSIGNOR TO UNION TANK CAR COMPANY, OF JERSEY CITY, NEW JERSEY, A CORPORATION OF NEW JERSEY.

DOME FOR TANKS AND METHOD OF MAKING THE SAME.

Application filed September 12, 1923. Serial No. 662,163.

My invention consists of certain novel parts and combinations of parts particularly pointed out in the claims. The following is a description of an apparatus for carrying out my invention in the form at present preferred by me, but it will be understood that various modifications and changes may be made without departing from the spirit of my invention and without exceeding the scope of my claims.

My invention will best be understood by reference to the accompanying drawings illustrating one embodiment of my invention in which Figure 1 is a perspective view, partially in section, illustrating a dome for a tank made in accordance with my invention; Fig. 2 is a vertical transverse section taken through the tank and dome therefor; and Fig. 3 is a vertical longitudinal section.

Like reference characters indicate like parts throughout the drawings.

Referring now to the drawings, 10 is a tank here shown as circular in form and of the type commonly mounted on vehicles and used for transporting or storing liquids. In the form shown the cylindrical portion of the tank is made of three sheets, a bottom sheet 10^a and two crown sheets 10^b and 10^c, the sheets being riveted together as at 11, in the usual manner. While I have illustrated my invention in connection with a tank made from three sheets, it will be understood that the same may be made from four or any other number of sheets. When made from four sheets, or any other number of sheets, the annular flange 13 is pressed or otherwise formed from the single top sheet.

In accordance with my invention, the dome for the tank indicated generally at 12 and through which liquids are charged into the tank and access generally obtained thereto, is partially formed by an annular flange 13 which is integral with the metal sheet of which the tank is formed. This annular flange, which is usually cylindrical in form, is made by either pressing or flanging or otherwise upsetting the metal of the sheet of which the tank is formed, and when there are two crown sheets, as illustrated, part of the flange 13 is formed from one of the crown sheets 10^b while the other part is formed from the crown sheet 10^c, the two parts being riveted together as at 14. A separately formed dome member 15 which is preferably formed

by a pressing operation, is made to telescope with the flange 13, and is secured thereto as at 16 by riveting. The dome member 15 is preferably formed with an annular portion 151 which is secured to the flange 13 and an inwardly extending portion 152 which serves as a cover and is shown as provided with the usual manhole 153. The annular circular flange which is integral with the metal sheet of the tank, therefore, forms the lower portion of the dome, the upper portion thereof being formed preferably by a one-piece dome member 15, which is secured to the flange 13 as by riveting at 16.

Domes of the general type illustrated herein, have commonly been made as a separate unit made up of one dome sheet and a dome head, the dome sheet being flanged at the bottom. The two parts are riveted together, and the lower flange then riveted to the tank sheet.

A dome formed in accordance with my invention, eliminates any dome flange seam, increasing the efficiency of the tank as there are less chances for leakage. Furthermore my invention reduces the large number of rivets used in riveting the dome to the tank and thus increases the efficiency of the tank as there are less chances for leakage. In addition, the operations involved in making a dome in accordance with my invention, may be carried out with machinery instead of by hand as has heretofore been necessary.

I claim:

1. In combination, a substantially cylindrical tank and a dome therefor formed in part by a substantially cylindrical flange integral with the tank sheet and extending laterally from the cylindrical portion of the tank and in part by a separate dome member secured thereto, the longitudinal axis of the dome being arranged at an angle to the axis of the tank.

2. In combination, a substantially cylindrical tank and a dome therefor formed in part by a substantially cylindrical flange integral with the tank sheet and extending laterally from the cylindrical portion of the tank and in part by a separate dome member having a cylindrical attaching portion by which it may be secured to said flange, the longitudinal axis of the dome being arranged at an angle to the axis of the tank.

3. In combination, a substantially cylindrical tank and a dome therefor formed in part

by a substantially cylindrical flange integral with the tank sheet and extending laterally from the upper cylindrical portion of said tank, and in part by a separate dome member secured to said flange, said dome member having an annular attaching portion and an inwardly extending portion forming a cover for the dome, the longitudinal axis of the dome being arranged at an angle to the axis of the tank.

4. In combination, a substantially cylindrical tank and a dome therefor comprising

a cylindrical flange formed integral with the crown sheet of said tank and extending from a side thereof at an angle thereto and intermediate the ends of the tank, and a separate dome member secured to said flange, said dome member having an annular attaching portion and an inwardly extending portion forming a cover for the dome, the longitudinal axis of the dome being arranged at an angle to the axis of the tank.

RAY MOSHER SMITH.
